F. P. KOBERT.
INSULATOR SUPPORT FOR ELECTRIC WIRES.
APPLICATION FILED JAN. 10, 1914.

1,110,496.

Patented Sept. 15, 1914.

UNITED STATES PATENT OFFICE.

FRANK P. KOBERT, OF NEW HAVEN, CONNECTICUT, ASSIGNOR TO THE BARNES & KOBERT MANUFACTURING COMPANY, OF NEW HAVEN, CONNECTICUT, A CORPORATION OF CONNECTICUT.

INSULATOR-SUPPORT FOR ELECTRIC WIRES.

1,110,496.

Specification of Letters Patent. Patented Sept. 15, 1914.

Application filed January 10, 1914. Serial No. 811,315.

To all whom it may concern:

Be it known that I, FRANK P. KOBERT, a citizen of the United States, and residing at New Haven, in the county of New Haven 5 and State of Connecticut, have invented certain new and useful Improvements in Insulator-Supports for Electric Wires, of which the following is a specification, such as will enable those skilled in the art to which it 10 appertains to make and use the same.

This invention relates to insulator supports for electric wires, and particularly to devices of this class designed for use in connection with the cross arms usually employed on electric wire poles or similar supports, and with this and other objects in view, the invention consists in a device, or devices of the class specified, constructed as hereinafter described and claimed.

20 The invention is fully disclosed in the following specification of which the accompanying drawing forms a part, in which the separate parts of my improvement are designated by suitable reference characters in each of the views, and in which:

Figure 1 is a cross sectional view of one of the cross arms used in connection with a pole or similar device, for the purpose of supporting electric wires, and showing my improvement applied thereto with the construction thereof partly in section;—Fig. 2 a section on the line 2—2 of Fig. 1;—Fig. 3 a section on the line 3—3 of Fig. 1, and;—Fig. 4 a section on the line 4—4 of Fig. 1.

35 In the drawing forming part of this specification, I have shown at *a* one of the cross arms usually employed in connection with a pole for supporting electric wires, and in the practice of my invention, I provide an insulator support for use in connection with said arm, and comprising a bottom member *b*, a top member *c*, and side members *d*, the top member *c* being provided with a vertical pin *e* with which the insulator *f* is 40 connected in the usual or any desired manner.

The bottom member *b* consists of a piece of channel iron which is longer than the transverse dimensions of the arm *a*, and the 45 end portions of which open downwardly, as shown at *b*², and the top or back of the end portions *b*² are provided with longitudinal slots *b*³ which are preferably extended into

the horizontal central portions of said part *b*, as shown at *b*⁴.

55 The top member *c* consists of a plate which is from two to three inches wide, and which is longer than the transverse dimensions of the arm *a*, and the end portions of which are bent upwardly, as shown at *c*², and said end portions are also provided with central longitudinal slots *c*³ which are preferably extended into the horizontal central portion of said plate, as shown at *c*⁴.

60 The side members *d* consist of bolts or rods passed upwardly through the slots or openings *b*³, and through the slots or openings *c*³, and one end of which, preferably the lower end, is provided with T-heads *d*² in the construction shown, but these heads may be spherical in form, if desired, and the other 65 ends of said rods, the upper ends, as shown, are provided with nuts *d*³ having convex or semi spherical bottom portions *d*⁴.

65 This construction, as will be seen, produces a strong and substantial frame which may be securely bound to, or secured to the arm *a*, and in the operation of turning the nuts *d*³ so as to tighten the bolts or rods *d* and bind the top and bottom members of said frame together, the bolts or rods *d* move inwardly and press against the sides of the arm *a*, and the top and bottom members are also drawn into close connection with the top and bottom of the arm *a* and this construction also adapts the device to arms of 80 different transverse and vertical dimensions, as will be readily understood.

85 The pin *e* is provided with a welded or otherwise formed head *e*² which is riveted to the plate *c* forming the top member of the frame, as shown at *e*³, or said pin may be secured to said plate in any desired manner.

90 The pin *e* may be of any desired length, and the insulator *f* may be connected therewith or secured thereto in the usual or any preferred manner, and changes in and modifications of the construction herein described may be made, within the scope of the appended claims, without departing from the 95 spirit of my invention or sacrificing its advantages.

100 It will also be understood that any desired number of bracket frames made in the manner described may be connected with the arm *a*, and will not in any way weaken or injure

said arm, and said devices may also be applied to other frames or supports.

Having fully described my invention what I claim as new and desire to secure by Letters Patent is:

1. The herein described means for securing insulators to the arm of a telegraph pole or other support, comprising a frame consisting of a bottom member, a top member, and two side rods, said side rods being provided at one end with nuts, and being passed through the end portions of the top and bottom members, said end portions of said top and bottom members being also provided with means whereby the operation of tightening said nuts will tighten the top and bottom members on the top and bottom surfaces of said arm and also draw said rods in close contact with the sides of said arm.
2. The herein described means for securing insulators to the arm of a telegraph pole or other support comprising a frame consisting of a top member, a bottom member

and side members, the bottom member extending transversely of the bottom of said arm and being longer than the transverse dimensions of said arm, and the end portions thereof being curved downwardly and provided with longitudinal slots, and the top member extending transversely across the top of said arm and being longer than the transverse dimensions thereof, and the end portions of said top member being curved upwardly and provided with central slots, and the side members consisting of rods passed through the slots in the end portions of said members and provided at one end with heads and at the other end with nuts.

In testimony that I claim the foregoing as my invention I have signed my name in presence of the subscribing witnesses this 29th day of December, 1913.

FRANK P. KOBERT.

Witnesses:

C. MULREANY,
S. ANDREWS.
